UNITED STATES PATENT OFFICE

SAMUEL GOLDSTEIN, OF BOSTON, MASSACHUSETTS

HANGER

Application filed November 23, 1932. Serial No. 644,036.

The present invention relates to hangers, and more particularly to hangers for supporting curtain and drapery rods.

Heretofore numerous devices have been provided for supporting curtain and drapery rods, but a number of disadvantages have been experienced in their use. Most hanging devices are secured to window frames by means of nails or screws which form holes in the woodwork. The presence of these holes is especially displeasing in the case of apartment houses because the holes detract from the appearance of a room to be let, and because each new tenant, in putting up his own fixtures, makes new holes. Nailed fixtures present a further disadvantage in any kind of dwelling because expert carpenters seldom apply the fixtures, and amateurs not infrequently miss the nails when hammering, thereby denting the woodwork.

Accordingly, it is the principal object of the present invention to provide a fastening-less hanger for supporting drapery and curtain rods without in any way marring or defacing the exposed faces of window frames.

To the accomplishment of this object, and such others as hereinafter appear, the features of the present invention consist in certain devices, combinations, and arrangements of parts, fully set forth hereinafter and then pointed out broadly and in detail in the appended claims, which possess advantages readily apparent to those skilled in the art.

The various features of the present invention will be readily understood from an inspection of the accompanying drawing illustrating the best form of the invention at present known to the inventor, in which,

Figure 1 is a detail view in perspective showing the hanger in use upon a window-frame;

Fig. 2 is a detail view in front elevation, a curtain rod and a curtain being indicated by construction lines, and

Fig. 3 is a detail view in left side elevation, the window-frame being shown partially in section.

The illustrated embodiment of the present invention is provided with a member 4 which is substantially parallel with the front face of a window-frame lintel 5. At its upper end the member 4 is bent rearwardly to form a flat portion 6 which rests upon the top 7 of the lintel 5 adjacent one end face thereof, as shown in Fig. 1. The member 4 may be pro-

vided, if desired, with a depending point 8 (Fig. 3) which bites slightly into the top of the lintel 5. At its lower end the member 4 is bent forwardly at right angles to the frame to form a short portion 9 and depending U-shaped folds 10 and 11, spaced apart by a portion 12 as shown in Fig. 1. The folds 10 and 11 support drapery rods 13 one of which is shown in Fig. 2. The portion 9 serves to space a curtain 14 from the window-frame, and the portion 12 serves to space the curtain from an over-drapery (not shown). None of the elements named is nailed or screwed to the lintel in any way. The structure merely depends from the top of the lintel.

The structure so far described might be used for supporting any object the weight of which is directed wholly downward, but difficulty arises in using such a structure when the weight, in addition to being directed downward, also exerts a lateral pull upon the supporting means. This lateral pull is relatively strong in the case of hanging draperies, since the supporting means is pulled inwardly both by the weight of the draperies, especially when being drawn together, and by the weight of the rod or rods. Since the member 4 and its bent portions are not nailed or otherwise fastened to the window-frame, it is desirable to provide means whereby this lateral pull is offset. To this end an arm 15 is pivoted to the member 4 by means of a pin 16, and the arm 15 is provided at its lower free end with a rearwardly bent portion 17 which engages the bottom of the lintel 5 in the corner formed by the lintel and the inside edge of the side frame. Both the member 4 and the arm 15 are provided with small holes 18 and 19, respectively, by means of which a coil spring 20 is hooked to the member 4 and the arm 15 to connect them. Preferably, as shown in Figs. 1 and 2, the hole 18 is placed adjacent the upper end of the member 4 and the hole 19 is placed well along the pivoted arm 15 to give the spring a maximum pulling power.

The hanger illustrated in the drawing is adapted to be placed at the upper right hand corner of a window-frame. A hanger identical with the one illustrated, except that the arm 15 extends to the right, viewing Figs. 1 and 2, is placed at the upper left hand corner of the frame, the folds in the manner 4 of each hanger serving to support drapery rod ends. The left hand hanger is made in the

same manner as the right hand hanger is made, the arm 15 being placed to the right of the member 4 instead of to the left when the spring 20 is attached. In fact each 5 hanger is itself reversible, since the arm 15 may be swung to either side of the member 4 after the spring is attached.

In using the present invention the bent portion 17 of the arm 15 is placed in abutment with the bottom of the lintel 5 as shown 10 in Figs. 1 and 2. The flat portion 6 is then placed in engagement with the top of the lintel 5 so that the member 4 and the folded portions 10 and 11 hang vertically. The 15 portion 6 may be then pressed down to cause the point 8 to bite slightly into the top 7 of the lintel. With the hangers in position draperies may be hung by placing the ends of the drapery rods 13 in the folds 10 and 11. 20 The bent portion 17 of the arm 15 on each hanger is caused to hug the corner hereinbefore referred to by means of the spring 20, and each structure is held rigid.

It will be seen that the present invention 25 provides a simple device comprising but four pieces by which draperies may be hung without the use of a single nail or screw to mar the exposed surfaces of the woodwork, and without the bother and difficulty always encountered in securing fixtures to window- 30 frames preparatory to hanging draperies.

The present invention has been described as being used to hang window draperies. It will be clear that the present invention works 35 equally well for hanging draperies for the frames of openings between rooms or for any frames presenting corners upon which the present invention may be used. Moreover, the pivoted arm 15 insures that the present 40 invention may be used regardless of the width of the lintel, since by swinging the arm 15 downwardly (Fig. 1) and moving the flat portion 6 along the top of the lintel the present invention may be used on lintels having 45 varying widths. The present invention need not be applied as illustrated, but may be used equally well if the right hand and left hand hangers be interchanged and the bent portion 17 of the arm 15 of each hanger be 50 placed in engagement with the corner formed by the bottom of the lintel and the outer edge of the side frame.

It will be clear to those skilled in this class 55 of devices and with the general objects of the present invention in view, that changes may be made in the details of structure, the described and illustrated embodiment thereof being intended as an exploitation of its underlying essentials, the features whereof are 60 definitely stated in their true scope in the claims herewith.

What is claimed as new, is:

1. A hanger comprising at least two arms pivoted together and adapted to engage 70 yieldingly the top and bottom of a lintel, respectively.
2. A hanger comprising at least two arms, pivoted together and provided with offset ends, adapted to embrace a lintel yieldingly.
3. In a hanger, the combination with at 75 least two arms pivoted together and adapted to engage the top and bottom of a lintel, respectively, of resilient means connecting the arms for allowing them to accommodate themselves yieldingly to lintels varying in width.
4. In a hanger, the combination with arms pivoted to each other and adapted to engage the top and bottom of a lintel, respectively, of a spring connecting the arms.
5. In a hanger, the combination with an 80 arm having its lower end bent to form a support and its upper end bent to engage the top of a lintel, and a second arm, pivoted to the first arm between its bent ends, having its lower end bent to engage the bottom of the lintel, of a spring connecting the arms.
6. In a hanger, the combination with an 85 arm having its lower end bent to form a support and its upper end bent to engage the top of a lintel, and a second arm, pivoted to the first arm between its bent ends, having its lower end bent to engage the bottom of a 90 lintel, of a coiled spring having one end connected to the first arm, between the pivot and the upper bent end, and having its other end connected to the second arm, between the pivot and the lower bent end.
7. In a hanger, the combination with an 95 arm adapted to engage the top of a lintel adjacent one end face thereof, and a second arm pivoted to the first arm and adapted to engage the bottom of the lintel in the corner formed by the lintel and a side frame, of 100 resilient means connecting the arms for providing a yielding resistance to a relative movement of the arms.
8. In a hanger, the combination with a member having a portion for supporting an article, and an arm pivoted to the member, of means secured to the member and to the arm providing a yielding resistance to a 105 swinging of the arm in one direction.
9. In a hanger, the combination with a member having a portion for supporting an article, and an arm pivoted to the member, of a coil spring connecting the member and the arm providing a yielding resistance to a 110 swinging of the arm in one direction.
- 115 In testimony whereof I have signed my name to this specification.

SAMUEL GOLDSTEIN.
